(57) CLAIM

The ornamental design for a mascara tube, as shown and described.

DESCRIPTION

Fig. 1.1 is a perspective view of a mascara tube.

Fig. 1.2 is a left side elevational view.

Fig. 1.3 is a bottom plan view.

Fig. 1.4 is a top plan view.

Fig. 1.5 is a right side elevational view.

Fig. 1.6 is a rear elevational view.

Fig. 1.7 is an additional elevational view.

In Fig. 1.7, the central portion of the mascara tube is shown separately for convenience of illustration.

The broken line disclosure is for the purpose of illustrating unclaimed portions of the article and forms no part of the claimed design.
